UNITED STATES PATENT OFFICE.

JOHN DARLING, OF AUGUSTA, INDIANA, ASSIGNOR OF ONE-HALF TO STEPHEN L. HAUGH, OF AUGUSTA, INDIANA.

PAINTER'S AND DECORATOR'S DISPLAY-RACK.

1,197,610.

Specification of Letters Patent. Patented Sept. 12, 1916.

Application filed February 19, 1916. Serial No. 79,438.

To all whom it may concern:

Be it known that I, JOHN DARLING, a citizen of the United States, residing at Augusta, in the county of Marion and State 5 of Indiana, have invented certain new and useful Improvements in Painters' and Decorators' Display-Racks, of which the following is a specification.

This invention relates to improvements 10 in racks for the convenient and proper exhibition of wall paper samples to prospective customers, and also of paints and other exterior as well as interior surface finishes, and the object is to provide a portable display device which can be folded into the 15 compass of a suit-case, containing all of the samples, and carried from house to house by an exhibitor.

A further object is to provide such a suit- 20 case structure as will be strong and durable as such, and which can be opened to form a display rack of practical utility, on very short order, one side of which will exhibit color schemes in paint and the like and the 25 other side of which will afford means for wall paper display whereby decorations for walls, ceilings and borders may be exhibited in their proper relations to each other without tiring the exhibitor.

30 A further object is to provide convenient carrying receptacles for rule, order-blanks, cards and the like accessories used by the salesman.

I accomplish the above, and other objects 35 which will hereinafter appear, by the mechanism illustrated in the accompanying drawings, in which—

Figure 1, is a perspective view of my invention folded in the form of a suit-case for 40 convenient carrying. Fig. 2 is a cross section on the line 2—2 of Fig. 1. Fig. 3 is a perspective view of the device opened in the form of a rack for displaying wall paper. Fig. 4 is a perspective view showing the suit 45 case opened up to form a rack for the display of paints and the like. Fig. 5 is a vertical section on the line 5—5 of Fig. 3. Fig. 6 is a perspective view of the rear or opposite side of the paper-display rack as 50 shown in Fig. 3, and Fig. 7, is a section on a larger scale illustrating the manner of hinging the front, back and middle suit-case members together.

Like characters of reference indicate like parts throughout the several views of the 55 drawings.

The device in its folded or closed condition as shown in Fig. 1, comprises a middle member 8, near the end of which sides 9 and 10 are hinged by screws 11, which pass 60 through lapped portions of all three of said members into a block 12 fixed rigidly at the hinge-corners of said middle member (see Fig. 7). The sides 9 and 10 have inwardly extending marginal flanges 13, which stiffen and strengthen their respective members, and also, by overlapping the middle member 8 as clearly shown in Fig. 2, 65 strengthen the folded or closed structure by hanging the weight of said sides directly 70 from said middle member. Thus, by attaching a hand-strap 14 to the latter the weight of all three members will be most advantageously supported from that one piece to which the hand-strap is fastened. 75 Hooks 15, attached to the side 9, hold the folded parts together by engagement with pins in the side 10.

The flanges 13 of the side members 9 and 10, are widened inwardly adjacent their 80 hinged ends to reach the hinge-screws 11, in median lines between the two sides. The added strength which this widening affords, permits me to form adjacent trays 16, 16, which trays are hinged to the body of that 85 side member of which it is an extension and a part. These trays are joined together by elastic bands 17, 17, preferably attached outside to the middle of each, and by normally drawing the trays toward each other, 90 holding them closed against the middle member 8 in the folded or suit-case form of the device, and in correct positions for use in its display-rack forms.

When the suit-case is opened up to form 95 a rack for the display of wall papers, the middle member 8 and side 9 are brought in oblique relation to each other with their ends on the floor, thereby forming a supporting base, and the other side 10 is raised 100 into alignment with the body 8, as shown in Figs. 3, 5 and 6. A wire loop 18 is attached to the cross bar 19, at the hinge-end of the member 8, and from this loop a book 20, of usual form, containing samples of wall pa- 105 per to be displayed, but provided by me

with a special hook 21, is suspended by the engagement of the hook 21, with said loop, as shown in Fig. 5. The book will rest against the board 22 of said member 8, and 5 when the salesman desires to show the inner or lower samples he turns the overlying sheets up and back and passes them down between the members 8 and 9, in the manner shown in Figs. 3 and 5, where they will 10 remain without any further attention, and out of the way. The remaining sheets can then be lifted one at a time to show the patterns, and the raised sheets held by a spring-clamp 26, fastened to the inside of the member 10. Any part of a sample-book can be 15 conveniently reached in this manner and the fatigue attending the holding of the sheets by the salesman during inspection by a customer is avoided, leaving him free to use his 20 energy in exploiting his merchandise.

The depth of the flanges surrounding the member 8, is such as to provide a receptacle which is ample to hold several sample books, particularly when the device is closed into 25 a suit-case. While making a display, all but the one book to be shown is preferably removed, and to aid in this removal I provide a metal strap 27 which normally rests against the board 22, between said board 30 and the books. The ends of this strap project out at right angles to it, within reach of the operator, so that by pulling on the strap-ends the strap will be drawn out and the books brought out within convenient 35 reach. The flanges of member 8 are cut in at 29 to further assist in reaching the books or the leaves of a book, in manipulating same. Metal straps 30, on the lower cross-bar of the middle member 8 support the lower ends 40 of the books.

It will be noted that the tray hinged to the member 10 supports the latter by bearing against the shoulder in the member 9 at the junction of member 9 with its tray, and 45 that the tray hinged to the member 9 is held by the elastic straps in a substantially horizontal position. This tray is provided with clips to hold business cards, order blanks, a measuring rule and the like articles helpful to the salesman, which are presented for convenient use.

An elastic strap 31 is adapted to be removably secured across the lower end of the member 8, as shown, to hold the books from 55 bagging down when the device is opened as shown in Fig. 4, to display the paint and color schemes. The strap 31 also holds the books in place while being carried in the 60 suit-case form of the device, as shown in Fig. 2. In the display rack of Fig. 4, the middle member 8 and the side 10 are obliquely placed to form the base, and the side 9 is elevated in line with member 8. The 65 space between the members 8 and 9 is covered by a curtain 32, the outer surface of

which, and also the contiguous surfaces of the members 8 and 9, afford areas for the display of color samples, stencils and anything else that a salesman using the invention would desire to show. By raising the curtain access is afforded to drawers 33, on each side of the loop 18, in which samples of oils, varnishes and the like may be carried. In this form of the invention the tray-member of the side 10 becomes horizontal and 75 affords another receptacle for accessories for the use of the salesman.

The operation of my invention has been so fully described in connection with the foregoing description that further elaboration is deemed unnecessary.

While I have described my invention with more or less minuteness as regards details of construction and arrangement, and as being embodied in certain precise forms, I do not 85 desire to be limited thereto unduly or any more than is pointed out in the claims. On the contrary, I contemplate all proper changes in form, construction and arrangement, the omission of immaterial elements 90 and the substitution of equivalents as circumstances may suggest or necessity render expedient.

I claim:

1. A folding display-rack comprising a 95 middle member and two side members, one on each side of said middle member, both side members being pivotally connected with an end of said middle member, said side members having hinged portions swinging 100 out of alignment with their body portions, one of said hinged portions contacting with the other lower side member to support said upper side member, and the hinged portion of the lower side member being in a substan- 105 tially horizontal position.

2. A folding display-rack comprising a middle member and two side members, one on each side of said middle member, both side members being pivotally connected with 110 the same end of said middle member, said side members having portions swinging out of alignment with their body portions, one of said hinged portions contacting with the other lower side member to support said upper side member, and the hinged portion of the lower side member being in a substan- 115 tially horizontal position.

3. A folding display-rack comprising a middle member and two side members, one 120 on each side of said middle member, both side members being pivotally connected with the same end of said middle member, said side members having hinged portions swinging out of alignment with their body 125 portions, one of the hinged portions contacting with the other lower side member to support said upper side member, the hinged portion of the lower side member being in a substantially horizontal position, 130

and elastic ties connecting said hinged portions with each other.

4. A folding display-rack comprising a middle member and two side members, one on each side of said middle member in the folded position of the rack, both side members being pivotally connected with the same end of said middle member and with each other, said side members having flanges 10 which overlap the middle member in the closed positions of said members, and means to support a member in its raised position.

5. A display-rack in foldable sections adapted to be folded together into the form 15 of a suit-case, and when opened having a space between them for the passage of turned-back leaves of a sample-book supported by one of said sections.

6. A display-rack in foldable sections 20 comprising a middle and two side sections between and to which the middle section is

hinged, said sections when opened into a rack having separating spaces for the passage of turned-back leaves of a sample-book supported by the middle section, one of said 25 sides being above the middle section in the rack-form of the device, and means on the raised section to hold up leaves of the sample book.

7. A display-rack in foldable sections 30 having a space between the sections when opened for the passage of turned-back leaves, and having a loop from which sample books are suspended, in combination with an outwardly adjustable strap means 35 to move the book in and out on the rack.

In witness whereof I have hereunto set my hand and seal at Indianapolis, Indiana, this 24th day of January, A. D. one thousand nine hundred and sixteen.

JOHN DARLING. [L. s.]
